UNITED STATES PATENT OFFICE

SAUL APTER, OF CINCINNATI, OHIO

DESIGN FOR A TRAVELING CASE

Application filed July 10, 1930. Serial No. 36,321. Term of patent 7 years.

To all whom it may concern:

Be it known that I, SAUL APTER, a citizen of the United States of America, and a resident of Cincinnati, in the county of Hamilton and State of Ohio, have invented a new, original, and ornamental Design for a Traveling Case, of which the following is a specification, reference being made to the accompanying drawing, forming part thereof.

Fig. 1 is a perspective view of a traveling case showing my new design.

Fig. 2 is an opposite perspective view of the traveling case of Fig. 1.

I claim:

The ornamental design for a traveling case, as shown.
